EQUIPMENT TRAILER FOR SERVICING PUBLIC UTILITY INSTALLATIONS

Thurman A. Pelsue, 3706 S. Hibiscus Way,
Denver, Colo. 80237

Filed May 4, 1967, Ser. No. 6,948

Term of patent 14 years

(Cl. D14—3)

FIG. 1.

FIG. 2.

FIG. 4.

FIG. 3.

FIGURE 1 is a top plan view of an equipment trailer for servicing public utility installations showing my new design;

FIGURE 2 is a left side elevation;

FIGURE 3 is a front elevation; and

FIGURE 4 is a rear elevation.

The right side elevation will appear as a mirror image of the left side elevation except that the cylindrical canisters will be hidden.

I claim:

The ornamental design for an equipment trailer for servicing public utility installations, as shown and described.
